UNITED STATES PATENT OFFICE

106,649

DESIGN FOR AN OVERSHOE

Edward F. Casey, Malden, Mass., assignor to Converse Rubber Company, Malden, Mass., a corporation of Massachusetts

Application April 10, 1937, Serial No. 68,662

Term of patent 14 years

To all whom it may concern:

Be it known that I, Edward F. Casey, a citizen of the United States of America, residing at Malden, in the county of Middlesex and Commonwealth of Massachusetts, have invented a new, original, and ornamental Design for an Overshoe, of which the following is a specification, reference being had to the accompanying drawing, forming a part thereof.

Fig. 1 is an elevational view of the outside of an overshoe, for the right foot of the wearer, showing my new design;

Fig. 2 is an elevational view of the opposite side of the shoe shown in Fig. 1.

I claim:

The ornamental design for an overshoe, substantially as shown.

EDWARD F. CASEY.
